B. LESLIE,
THERAPEUTIC CABINET,
APPLICATION FILED MAR. 1, 1915.

1,158,382.

Patented Oct. 26, 1915.

UNITED STATES PATENT OFFICE.

BONNAFORD LESLIE, OF CHICAGO, ILLINOIS, ASSIGNOR OF ONE-HALF TO S. D. ZAPHYRIADES, OF CHICAGO, ILLINOIS.

TERAPEUTIC CABINET.

1,158,382.

Specification of Letters Patent. Patented Oct. 26, 1915.

Application filed March 1, 1915. Serial No. 11,411.

To all whom it may concern:

Be it known that I, BONNAFORD LESLIE, a citizen of the United States, and a resident of Chicago, in the county of Cook and State 5 of Illinois, have invented certain new and useful Improvements in Therapeutic Cabinets; and I do hereby declare that the following is a full, clear, and exact description thereof, reference being had to the accompanying drawings, and to the characters 10 of reference marked thereon, which form a part of this specification.

This invention relates to improvements in therapeutic cabinets of that kind in which 15 a heated medium and a medicated vapor are applied to the body of the patient while reclining therein so as to induce perspiration and facilitate the penetration of the medicated vapor through the pores of the skin.

20 Among the objects of the invention is to produce an improved cabinet of this character so constructed and arranged as to provide for the direct application of the medicated vapor and heated medium to the body, 25 and also provide for a thorough and uniform admixture of the vapor and heated medium throughout the cabinet and a free circulation of the material through the conducting pipes.

30 Further objects of the invention are to improve and simplify cabinet constructions of this character, and the invention consists in the matters hereinafter set forth and more particularly pointed out in the appended 35 claims.

In the drawings:—Figure 1 is a side elevation of a therapeutic cabinet embodying my invention. Fig. 2 is a partial end view and partial transverse sectional view. Fig. 40 3 is a horizontal section taken on the general line indicated at 3—3 of Fig. 1. Fig. 4 is a fragmentary section view of one of the distributing pipes. Fig. 5 is a cross section on the line 5—5 of Fig. 3.

45 As shown in the drawings, 10, 11 designate the front and rear walls, respectively, of the cabinet box or inclosure and 12, 12 designate the end walls thereof. The cabinet is open at its top and is adapted to be 50 closed by a swinging lid or cover 14 hinged to one side wall. A portion of the front wall 10 comprises a drop door 15 to facilitate entrance to and exit from the cabinet. 16 designates a foraminated or open work support 55 on which the patient reclines during

the treatment, and upwardly through which the air and vapor passes for contact with the patient reclining on said support. The rear end wall of the cabinet is provided with an opening through which the head and neck 60 of the patient extends and with a head rest 17 to support the head of the patient while reclining in the cabinet.

Arranged within the cabinet beneath the 65 said support 16 are two pipes 18, 19, respectively, through the first of which is adapted to be circulated a medicated vapor, and through the latter of which is adapted to be circulated a heated medium. Each of 70 said pipes extends from the front end of the cabinet to a point near the rear end thereof and is connected by a return bend (20, 21) to the return portion of the pipe, giving a U-shape to each of the pipes. The 75 terminal 22 of the return portion of the vapor pipe is directed laterally through the rear wall 11 of the cabinet and, in practice, the out-turned terminal is connected with an exhaust pipe located outside of the apartment in which the cabinet is contained. No 80 means are herein shown for supporting the pipes in the cabinet, but it will be understood that they may be supported in a generally horizontal position therein in any 85 suitable manner.

The induction end of the vapor pipe is connected by a flaring mouth piece or funnel section 24 with a receptacle or retort 25 in which a medicated solution is heated to vaporize it, as by means of a suitable gas 90 burner therebelow; the vapor rising through the funnel section 24 and upwardly through the external vertical portion 26 of the induction end of the vapor pipe to circulate 95 backwardly through the cabinet and thence forwardly to the outlet terminal 22. The said vapor pipe is perforated to permit the escape of vapor into the cabinet, the perforations being preferably at the bottom of the pipe.

The induction end 28 of the dry air pipe, exterior to the cabinet, is formed with a flaring or funnel-shaped intake 29 which is located over a suitable burner in such manner as to direct the air heated by the burner 105 into the dry air pipe, the heated air circulating backwardly and forwardly through the continuous dry air pipe and escaping through a terminal 30, which may exhaust 110 through the front end wall of the cabinet.

The said exhaust terminal of the dry air pipe is provided with a valve 31 whereby the volume of air circulated through the pipe may be varied, and thereby the temperature to which the air is heated regulated. The dry air pipe is also perforated, preferably at its lower side, so as to permit the escape of dry air into the cabinet.

10 The bottom wall 33 of the cabinet tapers or inclines from both ends and from both sides thereof toward the central portion, at which is located a valved drain pipe 35, whereby moisture which accumulates in the cabinet may be drained or drawn off therefrom.

15 In the operation of the device the receptacle 25 is charged with a medicated solution, as a sulfur solution, and the receptacle is placed over a burner of a suitable stove 36, which stove may support the receptacle. The burner beneath the receptacle and also the burner beneath the flaring induction end 29 of the dry air pipe are thereafter lighted. The air heated by the burner 20 is circulated through the dry air pipe, and the vapor which rises from the receptacle 25 is circulated through the vapor pipe. The dry air and vapor are distributed uniformly through the cabinet by the perforated dry air and vapor pipes and mix with each other as they rise from the pipes toward the support 16. The volume of dry air passing through the pipe 19 is regulated by the valve 31 and, thereby the temperature 25 of the air delivered to the cabinet is varied. The volume of vapor circulating through the pipe 18 may be varied by regulating the burner flame below the receptacle 25. Thereby I am enabled to closely regulate 30 the temperature and the amount of medicated vapor delivered into the cabinet. The passages through the pipes from the induction ends to the outlet terminals thereof are direct, so that the regulation may be effected without being influenced by eddying or counter currents in the pipes. Thereby I am enabled to eliminate or avoid local 35 excessive temperatures, such as would be uncomfortable to the patient. Moreover, by reason of the delivery of the dry air and the vapor into the cabinet and its thorough admixture before it rises into contact with the body of the patient, I am enabled to secure a uniform mixture of the air and vapor, so as to apply as strong or as mild a treatment 40 of the vapor to the patient as desired while, at the same time, I am enabled to regulate the temperature of the resultant mixture without varying the proportions as to vapor 45 and dry air.

50 The location of the perforations of the pipes on the lower sides thereof contributes to a more efficient mixing of the heated air and vapor, inasmuch as the air and vapor rise on both sides of the pipes from their

55 points of discharge through the perforations so that the rising streams of air and vapor cross each other in larger areas of contact than if the air and vapor escaped wholly through perforations at the tops of the 60 pipes.

65 Preferably the dry air pipe is placed between the members of the vapor pipe. A practical advantage of this arrangement is that it is usually desirable to shut off the 70 dry air before the vapor is shut off, and the arrangement of the vapor pipe adjacent to the sides of the cabinet, especially when provided with bottom perforations, affords superior distribution of the vapor to the body 75 of the patient.

80 It is preferable to arrange the outlet terminal of one pipe adjacent to the inlet of the other pipe. In this way, the hottest air is brought into contact with the coolest 85 vapor and vice versa, thus contributing to the maintenance of an approximately uniform temperature throughout the cabinet.

85 In practice, it is preferable to arrange the perforations in the pipes 18, 19 off the center 90 lines of the pipes, with the perforations of adjoining limbs of different pipes located on the sides of the pipes adjacent to each other, as indicated in dotted lines in Fig. 3 and in full lines in Fig. 5. This relative arrangement of the perforations directs the vapor and dry air which issues from the adjoining limbs of the pipes toward each other so as to thereby assist in the proper admixture 95 thereof.

100 I claim as my invention:—

105 1. A therapeutic cabinet comprising an elongated inclosure, a foraminated support stretched across the same, non-communicating heated medium and vapor pipes arranged side by side within the inclosure beneath said support and extending from end to end thereof and perforated throughout their lengths at their lower sides in a manner to intermingle the material escaping 110 from the pipes in a plane below the pipes, said pipes extending through one wall of the inclosure, with separate means exterior to said wall to supply heated medium and heated vapor to the respective pipes, and the 115 pipes being arranged to provide free and unhampered passageways for the material therethrough whereby the heated medium and vapor are distributed uniformly to the inclosure throughout the length of the inclosure and intermixes and rises upwardly 120 through the foraminated support, and separate exhausts for said pipes extending outside the casing.

125 2. A therapeutic cabinet comprising an elongated inclosure, a foraminated support suspended thereacross, a U-shaped heated medium pipe within the inclosure below said support with its induction end extending through one wall of the inclosure, means to 130

- supply a heated medium to said pipe, a separate U-shaped vapor pipe within the inclosure with its limbs lying between the limbs of the heated medium pipe and the 5 side walls of the inclosure, and with its induction end extending through the wall of the inclosure, and means to supply a heated vapor to the induction end of the vapor pipe, said pipes being perforated throughout their 10 lengths in a manner to intermingle the heated media discharged therefrom in a plane below the pipes whereby the mixed heated medium and vapor rise upwardly through the foraminated support.
- 15 3. A therapeutic cabinet comprising an elongated inclosure, a foraminated support suspended thereacross, a U-shaped heated medium pipe within the inclosure below the said support with its induction end extending 20 through one wall of the inclosure and with the eduction end extending outside the inclosure, means to supply a heated medium to said pipe, a U-shaped vapor pipe within the inclosure with its limbs lying between the 25 limbs of the heated medium pipe and the side walls of the inclosure, and with its induction and eduction ends extending to the exterior of the inclosure, means to supply a heated vapor to the induction end of the 30 said vapor pipe, said pipes being perforated
- throughout their lengths, whereby the heated medium and vapor escaping therefrom intermingle within the inclosure and rise upwardly through the foraminated support, the induction end of the said heated medium 35 pipe being located closely adjacent to the eduction end of the vapor pipe, and vice versa.
4. A therapeutic cabinet comprising an elongated inclosure, an elongated support 40 therein for the patient, non-communicating pipes within the inclosure below the said support and arranged side by side throughout the length of the inclosure and provided with separate outlets and separate means to 45 supply material to the induction ends of the said pipes, said pipes being provided within the inclosure with escape openings to direct the different material downwardly and toward each other whereby the materials are 50 intimately intermingled before they rise to said support.

In testimony that I claim the foregoing as my invention I affix my signature in the presence of two witnesses, this 26th day of 55 August, A. D. 1914.

BONNAFORD LESLIE.
